UNITED STATES PATENT OFFICE.

ARCHIBALD H. WELLS AND JOHN D. KELLOGG, OF SEATTLE, WASHINGTON.

LATHE DRIVE-DOG.

1,323,134.

Specification of Letters Patent.

Patented Nov. 25, 1919.

Application filed February 3, 1919. Serial No. 274,677.

To all whom it may concern:

Be it known that we, ARCHIBALD H. WELLS and JOHN D. KELLOGG, citizens of the United States, at present residing at Seattle, in the 5 county of King and State of Washington, have invented certain new and useful Improvements in Lathe Drive-Dogs, of which the following is a specification.

Our invention relates to certain new and 10 useful improvements in lathe drive dogs especially adapted for use in bolt making and in its general nature the invention is a modification of our invention disclosed in our application filed January 6, 1919, Serial 15 No. 269,854.

In that application we disclosed a form of an invention which is especially adapted for heavy work on large lathes but, in the present case, the form disclosed has been especially 20 designed for small work and the present invention has for its object to reduce the weight of the parts and reduce the number of bolts necessary to hold the base plate or bracket member to the face of the lathe head 25 plate and still allow for the necessary adjustment.

In its detailed nature, the invention provides a base plate bracket consisting of a somewhat V-shaped body having an elongated 30 slot to fit over the lathe center and lie against the lathe head plate to which it is secured by a single bolt passing through the lower end of the body, the body being bent over at right angles at the top to form a flat 35 top portion to receive the adjustable jaws.

In its more detailed nature, the invention resides in those novel features of construction, combination and arrangement of parts, all of which will be first fully described and 40 then be specifically pointed out in the appended claims and illustrated in the accompanying drawings, in which:

Figure 1 is a perspective view showing our invention in use.

Fig. 2 is a perspective view of the base bracket member.

Fig. 3 is a perspective view of the finger members or clamps separated.

In the drawing in which like numerals of 50 reference indicate like parts in all of the figures, 1 represents the lathe head plate which is of the usual construction.

The base bracket which constitutes the feature of essential difference over the construction shown in our copending application, consists of a flat body 3 of triangular

form which is provided with a portion 2 bent at right angles to form a plate extending at right angles to the body part 3, the plate 2 having bolt holes 5 through which the bolts 12 may pass, the bolts 12 serving to adjustably secure the finger members 8 to the plate 2 through the medium of the bases 6 of the finger members, the said bases having slots 7 through which the bolts 12 pass to adjustably secure the fingers 8 in position to engage the sides of the head 9 of the bolt 10.

11 designates the bolt which secures the member 3 to the head plate 1, the bolt passing through the opening 4.

In use, the parts are assembled as indicated in Fig. 1, the lathe center 13 projecting through the elongated hole 14 in the body 3, the hole 14 extending in the horizontal direction of that body so that the same may be adjusted in one direction, while the members 8 may be adjusted in a direction transversely thereto, thus allowing for such adjustments of the fingers 8 as may be necessary to fit different size bolt heads, as will be clear to those skilled in the art.

From the foregoing description taken in connection with the accompanying drawings, it is thought the complete construction, 85 operation and advantages of the invention will be clear to those skilled in the art.

What we claim is:

1. A lathe drive dog comprising a base member having a base plate and a flat body portion at right angles thereto, the base plate having bolt holes and the body portion having an elongated slot through which the lathe center is adapted to project, when the device is in use, said body part having a bolt hole through which the same may be secured to the lathe head plate, a pair of finger members, each comprising a longitudinally slotted base plate adapted to lie in engagement with the base plate of the base member and having a finger pendent from one end of the finger base plate, and means for clamping the finger plates together to the base plate, all being arranged whereby the position of the dog on the head plate may be adjusted in a direction at right angles to the adjustment of the finger members with respect to the base plate, said finger members being independently adjustable on the base plate, substantially as shown and described.
2. As a new article, a lathe dog base mem-

ber comprising a body plate having an elongated slot adapted to fit onto the face of a lathe head plate with the lathe center projecting through the slot, said base member 5 also including a section extending at right angles to the plane of the body member and provided with bolt holes, and finger mem-

bers independently secured to said section for lateral adjustment parallel with respect to the plane of the body member, substantially as shown and for the purpose described.

ARCHIBALD H. WELLS.
JOHN D. KELLOGG.
